ATTORNEYS.

UNITED STATES PATENT OFFICE.

JOHN L. HEWITT, OF PHILADELPHIA, PENNSYLVANIA.

SIGN.

Application filed May 10, 1923. Serial No. 638,001.

To all whom it may concern:

Be it known that I, JOHN L. HEWITT, a citizen of the United States, residing at Philadelphia, county of Philadelphia, and State of Pennsylvania, have invented certain new and useful Improvements in Signs, of which the following is a specification, reference being had to the accompanying drawings.

10 This invention relates generally to signs for advertising or announcement purposes, and it has more particular reference to devices of the character adapted for attachment on walls, doors and similar structures, said signs being of a more or less permanent nature, or not intended for periodic change and variation. More specifically my invention comprehends improvements in what may be conveniently termed "flat" signs protected with a glass or other transparent outer facing against climatic or accidental disfigurement. Hereinafter whenever I use the term "flat" sign it is to be understood as referring to a sign embodying a glass or other transparent facing member having the sign suitably depicted on its under or non-exposed surface, in conjunction with a backing of appropriate protective material.

20 30 The primary object of this invention is to provide a novel structure of "flat" sign embodying means for effectively preventing the ingress of destructive matter to the back thereof, whereby the life and artistic character of said sign are carefully preserved.

Another object of my invention comprehends the provision of a glass protected "flat" sign having no nail or screw holes therethrough that tend to mar its beauty, as well as detrimentally affect its durability.

40 Further objects of this invention are, to improve and simplify the construction of "flat" signs, while diminishing their cost in manufacture, and increasing their effectiveness in use.

With the foregoing and other objects in view my invention consists essentially of a back member of durable and non-corrosive material, having its peripheral edges upwardly and inwardly flared for gripping engagement upon the correspondingly but reversely flared perimeter of a plate glass facing with the sign appropriately painted, carved, marked, cemented or otherwise depicted on the back thereof, said back mem-

ber having perforated extensions whereby the device may be secured in place.

In the further disclosure of the invention reference is to be had to the accompanying sheet of drawings constituting a part of this specification, and in which like characters of reference designate the same or corresponding parts in all the views, the same being illustrative by way of example only of one practical embodiment of the said invention.

Figure I is a face view of a "flat" sign in accordance with this invention.

Figure II is an end view of the same.

Figure III is a central longitudinal section through the showing in Figure I; and

Figure IV is a transverse section of the same.

Referring more in detail to the drawings and in accordance with my invention the novel flat sign generally characterized by

25 the numeral 5, comprises a back member 6 of appropriate non-corrosive sheet metal susceptible of receiving a more or less permanent degree of polish. This back member 6 is conveniently of substantially rec-

20 tangular formation in plan thereby providing parallel longitudinal sides or edges 7, 7, and opposed segmental ends 8, 8, the latter being provided with one or more nail

35 or screw holes 9, for the passage of nails or screws, whereby the "flat" sign 5 is secured against a wall or other structure in the very obvious and well known manner.

The aforesaid longitudinal edges 7, 7, are bent at substantially right angles to the

40 plane of the main portion of the back member 6 to provide outstanding flanges 10 for a purpose hereafter explained. Trans-

versely relative to the aforesaid back mem-

45 ber 6 are a pair of opposed end members or angled strips 11, 11, of the same sheet ma-

50 terial from which said back member is made, and said angled strips 11, embody relatively long or spacing flanges 12, and short outstanding flanges 13 adapted to reg-

55 60 65 70 75 80 85 90 95 100 105 110

ister with the flanges 10 hereinbefore referred to. Thus it will be seen that when the angled strips 11, 11, are in assembled relation between the longitudinal outstanding flanges 10 there is provided what may be aptly described as a shallow tray structure which constitutes a casing for the sign proper or facing member 14.

This sign proper or facing member 14 is preferably made of plate glass, rectangular

in plan, and of lineal dimensions to fit snugly within the plane surface bounded by the above described outstanding flanges 10, 10, and 13, 13. The peripheral edges of the plate glass facing member 14 are either beveled or angularly chamfered to provide evenly distributed and reversely opposed side and end scallops 15, 16, respectively. Said plate glass facing member 14 is suitably backed or coated with an opaque tissue 17 of appropriate character having the sign or announcement 18 appearing in exposed relation thereto. Or, the sign or announcement 18 may be appropriately painted, cut, cemented or otherwise secured to the back of the plate glass member 14 with the opaque tissue 17 coated on the aforesaid back 6.

In assembling the sign 5 it will be apparent that the necessary advertising or announcement matter 18 is firstly depicted on the back of the plate glass 14 and allowed to properly adhere thereto. The angled strips 11 are next placed in position between the outstanding flanges 10, as before set forth, with the plate glass 14 seating on the spacing flanges 12. Thus it will be readily seen that the flanges 12 space the advertising or announcement matter from actual contact with the back member 6 thereby protecting same from disfigurement. The peripheral outstanding flanges 10, 13 are now crimped or suitably expanded into gripping engagement with the aforesaid side and end scallops 15, 16, while the ends of the flanges 10 are clinched by a fold over 19 into secure frictional contact with the abutting ends 20 of the flanges 13. Thus it will be remarked that the several parts are securely connected together into a substantially unitary structure, while a neat and attractive wall or other structure "flat" sign 5 is provided.

Obviously the angled strips 11 may be securely attached by their spacing flanges 12 to the back member 6 in any of the well known ways, while the fold over ends 19 may be cemented or otherwise immovably connected to the abutting ends 20 to ensure an unbreakable joint thereat. Furthermore it is to be noted, that by making the sign matter or announcement 18 of luminous or phosphorescent material the device will be clearly discernible after dark without the necessity for associated illumination; while a fiber or other suitable material cushioning layer 21 is interposed between the back of the glass 14 and the angle strips 11, 11 to protect the announcement matter from damage by an accidental blow or other shock.

From the foregoing it will be clearly apparent that by my invention there is provided, a simple, cheap, and durable sign or advertising device, the same possessing attractive and artistic characteristic features that will commend said device for ready use in diversified situations. While I have

shown and described one practical design and embodiment of my invention it will be apparent the same is susceptible of modification in contour or pattern, therefore the right is hereby reserved to make such reasonable variation therein as fairly lies within the scope of the appended claims. 70

Having thus described my invention, 1 claim:

1. A device of the character described, 75 comprising a back member having edges affording a yieldable outset angled perimeter, a superposed transparent face member having an inwardly scalloped peripheral edge and bearing advertising matter, said outset perimeter being adapted for compression into frictional engagement with the inwardly scalloped peripheral edge of said face member, and supporting portions integral with the back member but independent 80 of the face member. 85

2. A device of the character described, comprising a substantially rectangular back member having integral parallel angled edges and opposed curved ends, angled strips 90 disposed in spaced relation between the aforesaid parallel angled edges, a superposed transparent face member having sign matter on its under surface, said face member being disposed between the angled edges 95 and adapted for frictional engagement thereby, and the aforesaid curved ends constituting a supporting means independent 100 of the face member. 105

3. A device of the character described, 100 comprising a substantially rectangular back member having parallel angled edges and opposed curved ends, angle strips disposed in spaced relation between the aforesaid parallel angled edges, a superposed transparent 105 face member bearing announcement matter seated on the angle strips between the parallel angled edges in spaced relation to the back member, all of said angled edges being adapted for flexure into frictional contact with the aligned edges of the face member, and the aforesaid curved ends constituting a supporting means independent of a face member. 110

4. A device of the character described, 115 comprising a substantially rectangular member having integral parallel angled edges and opposed curved ends, angle strips disposed in spaced relation between the aforesaid parallel angled edges, a superposed transparent face member having inclined edges and bearing sign matter seated on the angle strips between the parallel angled edges in spaced relation to the back member, all of said angled edges being adapted for compression into frictional impingement with the incline edges of the face member, and the aforesaid curved ends constituting a supporting means independent of a face member. 120 125 130

5. A device of the character described, comprising a substantially rectangular back member having integral parallel angled edges and opposed curved ends, parallel angle strips between the aforesaid angled edges and disposed at right angles thereto, a superposed transparent face member bearing advertising matter seating on the angle strips between the angled edges, all of said 10 angled edges being adapted for flexure into frictional engagement with the aligning edges of the said face member, the aforesaid curved ends constituting a supporting means independent of the face member, and the ends 15 of the aforesaid parallel edges being angularly folded over into engagement with the abutting ends of the angle strips.

6. A device of the character described comprising a substantially rectangular sheet 20 metal back member having parallel angled edges and opposed curved ends, sheet metal angle strips disposed in spaced relation between the aforesaid angled edges at right angles thereto, a superposed transparent face 25 member bearing announcement matter seating on the back member and having scalloped edges, all of the angled edges being adapted for compression into contact with the scalloped face member edges, the aforesaid curved ends constituting a supporting 30 means independent of the face member, and the ends of the angled parallel edges being inter-engaged by the abutting ends of the angled strips.

35. 7. A device of the character described comprising a substantially rectangular sheet metal back member having parallel angled edges and opposed curved ends, sheet metal angle strips disposed in spaced relation be- 40 tween the aforesaid angled edges at right angles thereto, a superposed transparent face member bearing an announcement seating between the angled edges, said face member having opposed edges reversely scalloped for 45 frictional engagement by the aligned angle edges, the aforesaid curved ends constituting a supporting means independent of the face member, and the end portion of the aforesaid parallel edges being adapted by 50 angular clinching to be brought into locked engagement with the abutting ends of the spaced angle strips.

8. A sign comprising a substantially rectangular non-corrosive sheet metal back having parallel outwardly angled edges and 55 opposed curved ends, non-corrosive sheet metal angle strips seated in spaced relation be-

tween the projecting flanges of the angled edges, a superposed plate-glass member having announcement matter depicted on its under surface and adapted to seat between the angled edges and strips, said face member having a beveled perimeter adapted for frictional engagement by the aligned projecting flanges, the aforesaid curved ends 60 providing a supporting means independent of the face member, and the end portions of the parallel edges being adapted by angular clinching to be brought into locked engagement with the abutting ends of the 65 spaced angle strips.

9. A sign comprising a non-corrosive sheet metal back having parallel outwardly angled edges and opposed curved ends, non-corrosive sheet metal angle strips arranged 70 in spaced relation between the projecting flanges of the angled edges, a plate glass member having announcement matter depicted on its under surface seated between the aforesaid projecting flanges and angle 75 strips, said face member having a scalloped perimeter adapted to be frictionally engaged by the aligned projecting flanges, the aforesaid curved ends providing a supporting means independent of the face member, and the end portion of the parallel outwardly angled edges being clinched into 80 locked engagement with the abutting ends of the spaced angle strips.

10. A sign comprising a non-corrosive sheet metal back having parallel outwardly angled edges and opposed curved ends, non-corrosive sheet metal angle strips arranged 85 in spaced relation between the projecting flanges of the angled edges, a plate glass member having announcement matter luminously depicted on its under surface seated between the projecting flanges and angle strips, said face member having a scalloped perimeter adapted to be frictionally engaged 90 by the aligned projecting flanges when compressed thereon, the aforesaid curved ends providing a supporting means independent of the face member, and the end portion of the parallel angled edges being clinched into 95 snap engagement with the abutting ends of the spaced angle strips.

In testimony whereof, I have hereunto signed my name at Philadelphia, Pennsylvania, this 7th day of May, 1923.

JOHN L. HEWITT.
